UNITED STATES PATENT OFFICE.

HARRY BERLOW, OF NEW YORK, N. Y.

ATTACHMENT DEVICE.

Application filed January 11, 1921. Serial No. 436,589.

To all whom it may concern:

Be it known that I, HARRY BERLOW, a citizen of the United States, residing at New York, county and State of New York, 5 have invented certain new and useful Improvements in Attachment Devices, of which the following is a specification.

This invention relates to an attachment device for cleaning mops and brushes and 10 primarily aims to provide a medium for detaching such mops and brushes readily and, which at the time when attached, will maintain a firm and rigid handle.

Other objects as well as the nature, characteristic features and scope of my invention will be more readily understood from 15 the following description, taken in connection with the accompanying drawings and pointed out in the claims forming a part of 20 this specification.

Figure 1 of the drawing, representing by way of example a practical embodiment of the invention, is a side elevation of the improvement.

25 Figure 2 is a sectional side elevation of the improvement and Figure 3 is a cross-sectional view on the line 3—3 of Fig. 1; Fig. 4 shows both parts of the joint separately, the slotted tube as a side elevation 30 and the other part, containing the pressure coil, as a sectional view; Fig. 5 finally represents a perspective view of the slotted tube.

As illustrated in Figure 1 an object in 35 the form of a cleaning mop is held by a wire rope 2 secured with its free ends within the smooth end of tube 3 which at its other end is provided with a slot 4 having an extension 5 at right angle with slot 4 and 40 the further extension 6 being parallel with slot 4, the slots 4, 5 and 6 therefore forming a kind of hook like incision into tube 3. A similar system of slots 7, 8 and 9 are provided diametrically opposite to slots 4, 45 5 and 6, with the difference however that slot 8 runs in the opposite direction from that of slot 5 and that consequently also slot 9 is located oppositely to slot 6. Tube 10 is bent at approximately its middle and 50 affixed to the end 14 of handle 12. A pin 13 is rigidly secured within tube 10 at a distance which corresponds approximately one half of the length of slot 4. Between the end 14 of handle 12 and pin 13 within 55 the tube 10 there is a plate 15 movably arranged, a spring 16 being furthermore in-

terposed between said plate 15 and end 14 of handle 12.

In case I do not use the cleaning device I detach tube 3 with the mop proper from 60 the handle and store each part in any manner convenient to me; if I want to use the device I slip tube 10 over tube 3 which fits telescopically into the former, and as pin 13 enters the slots 4 and 7 it is obvious that 65 from this moment the rim 17 of tube 3 presses plate 15 against spring 16 which recoils thereby. As soon as pin 13 has passed the full length of slots 4 and 7 the handle 12, or tube 10, respectively, is turned 70 by a twist of the hand to pass pin 13 through slots 5 and 8 and after they are passed spring 16 extends again to press pin 13 against the ends of slots 6 and 9. It is obvious therefore that tube 3 is held by three 75 different means to tube 10, by the wall of tube 10, by the rear ends of the bayonet slots 6 and 8, which spring 16 presses against pin 13, and by the plate 15, same being pressed against rim 17 of tube 3 by 80 spring 16.

Having now described my invention what I claim is:

1. An attachment device of the character as described, consisting of a metal tube having at one end diametrically opposite to each other two slots, having their hook shaped ends running in opposite directions, and at the other end the ends of a wire rope rigidly secured therein, another tube telescopically fitting over the tube referred to above, a pin rigidly secured within the latter tube, a handle secured to same, an annular plate movably arranged within said tube behind the pin, and a spring interposed between 90 said plate and the handle.

2. As a new article of manufacture an attachment device of the character as described, consisting of a metal tube having at one end diametrically opposite to each other two slots having their hook shaped ends running in opposite directions, and at the other the ends of a wire rope rigidly secured therein, another tube telescopically fitting over the tube referred to above, a pin rigidly secured within the latter tube adapted to enter the ends of the aforesaid hooks, a handle secured to aforesaid tube, an annular plate movably arranged within said tube behind the pin, and a spring interposed between said plate and the handle.

HARRY BERLOW.
